UNITED STATES PATENT OFFICE

LAWRENCE S. LAMB, OF DETROIT, MICHIGAN, ASSIGNOR TO HUDSON MOTOR CAR COMPANY, OF DETROIT, MICHIGAN, A CORPORATION OF MICHIGAN

APPARATUS FOR CLOSING SHEET-METAL CHANNEL MEMBERS

Application filed December 12, 1927. Serial No. 239,233.

This invention relates to shaping of sheet metal of substantially channel form to close a portion of the open side, and particularly to apparatus for forming windshield flanges on the front body pillars of metal automobile bodies.

It is an object of the invention to provide an apparatus of simple construction which will operate rapidly and efficiently for shaping articles of this type.

Before explaining in detail the present invention, and the method or mode of operation embodied therein, it is to be understood that the invention is not limited in its application to the details of construction and arrangement of parts illustrated in the accompanying drawings, since the invention is capable of other embodiments and of being practised in various ways. Also it is to be understood that the phraseology or terminology employed herein is for the purpose of description and not of limitation, and it is not intended to limit the invention beyond the terms of the several claims hereto appended or the requirements of the prior art.

In accordance with the invention, a machine is provided having a mandrel adapted to fit within the channel form, such as a pillar or other partially shaped article and which is positioned between dies which are movable relatively to shape the article to its predetermined form, suitable means being provided for holding the article and mandrel against one of the dies during their relative movement.

The invention will be more clearly understood from the following description in conjunction with the accompanying drawings, in which:

Fig. 1 is a plan view of the lower die member;

Fig. 2 is a plan view of the upper die member;

Fig. 3 is a sectional elevational view taken upon the line 3—3, Fig. 2, and showing the relation of the parts at the beginning of the forming operation;

Fig. 4 is a similar sectional view showing the relation of the parts at the completion of the forming operation;

Fig. 5 is a sectional view upon the line 5—5, Fig. 1;

Fig. 6 is a fragmentary horizontal section of a portion of an automobile body showing a front body pillar having a flange formed by mechanism embodying the invention, together with the door, windshield and associated parts;

Fig. 7 is a perspective view partly in section of the front body pillar before the forming operation; and

Fig. 8 is a similar view after the forming operation.

The type of metal automobile body to which the invention is directed particularly comprises a front body pillar 10, and a door 11 having a door pillar 12 adapted to close against the rear side of the pillar 10. A windshield 13 is adapted to close against the windshield flange 14 of the body pillar 10.

The present invention is particularly directed to an apparatus for forming the windshield flange 14 from a body pillar blank of the type shown in Fig. 7. A suitable apparatus for this purpose comprises a base 20 having a lower die member 21 secured thereto in any suitable manner as by bolts 22 and has its upper surface shaped to receive the rear side of the pillar. A projection 23 extends upwardly from one side of the base and is provided at its inner top edge with a wearing block 24 secured thereto in any suitable manner as by bolts 25. The projection 23 is reinforced by suitable webs 26, 27 and 28. Guides 30 for a reciprocable upper die member 31 are suitably mounted in the base 20.

An arm 35 is pivotally mounted between the webs 27 and 28 to turn about a hinge pin 36 and is normally held yieldingly in raised position above the lower die member 21 by springs 37 extending between openings 38 and 39 in the arm 35 and base 20 respectively. A mandrel 40 is mounted on the free end of the arm 35 by a dovetail connection, generally indicated at 42, and is secured thereto by bolts 43.

The upper die member 31 is provided with suitable guideways 45 to receive the guides 30 and is also provided with a guiding surface 46 cooperating with the wearing block 103.

24 upon the base. A suitably shaped wearing block 50 is secured, as by bolts 51, upon the lower portion of the upper die member 31 in a position to shape the flange 14 about the mandrel and against the lower die member 21. A work gripping member 53 is mounted to move in a guide opening 54 in the member 31 and is held therein in any suitable manner as by bolts 55 passing through openings 56 in the member 31 each of which is provided with a shoulder 58 adapted to engage the head 59 of the bolt and serve as a stop. The member 53 is normally held extended, with the head 59 of the bolt engaging the shoulder 58, by springs 60 extending between openings 61 and 62 in the member 31 and member 53 respectively.

When the apparatus is not operating the mandrel 40 is normally held above the lower die member 21 and spaced from the upper die member. The pillar 10 or other article to be shaped is placed over the mandrel 40 and the upper die member 31 is moved toward the lower die member thereby bringing the gripping member 53 into engagement with the pillar and causing the pillar carried by the mandrel to move against the lower die member 21. Further downward movement of the upper die member 31 compresses the springs 60 thereby causing the gripping member 53 to hold the work with a yielding pressure while the upper die moves downward to bring the block 50 against the flange of the work to shape it about the mandrel and against the lower die member.

What I claim is:

1. In an apparatus for shaping an automobile body front pillar to provide a windshield flange, the combination of lower and upper dies movable relatively to shape said flange, and a mandrel to fit within the pillar and movable between said dies, said upper die including a yielding member adapted to grip the pillar on said mandrel and move the same against said lower die when said lower and upper dies are moved relatively.

2. In an apparatus for shaping an automobile body front pillar to provide a windshield flange, the combination of a lower die, an upper die movable towards said lower die, a pivoted mandrel adapted to fit within the pillar, a spring normally holding said mandrel yieldingly above said lower die, said upper die including a yielding member adapted to grip the pillar on said mandrel when said upper die is moved towards the lower die.

3. In an apparatus for shaping an automobile body front pillar to provide a windshield flange, the combination of a lower die, an upper die movable towards said lower die, a pivoted mandrel adapted to fit within the pillar, a spring normally holding said mandrel yieldingly above said lower die, said upper die including a yielding member

adapted to grip the pillar on said mandrel when said upper die is moved towards the lower die, the adjacent surfaces of said mandrel and lower and upper dies being substantially parallel.

In testimony whereof I affix my signature.

LAWRENCE S. LAMB.
